UNITED STATES PATENT OFFICE.

WILLIAM LIPP HARRIS, OF SPRINGFIELD, OHIO, ASSIGNOR TO THE SPRINGFIELD MOTOR SWEEPER COMPANY, OF SPRINGFIELD, OHIO, A CORPORATION OF OHIO.

GUTTER BRUSH FOR STREET SWEEPERS.

Application filed December 14, 1923. Serial No. 680,704.

To all whom it may concern:

Be it known that WILLIAM LIPP HARRIS, a citizen of the United States, residing at Springfield, in the county of Clark and 5 State of Ohio, has invented certain new and useful Improvements in Gutter Brushes for Street Sweepers; and he hereby declares that the following is a full, clear, and exact 10 description thereof, reference being had to the accompanying drawings, which form part of this specification.

This invention relates to the gutter brushes for street sweepers, which brushes are usually located at the sides of the 15 sweeper and are mounted on a substantially vertical revolvable shaft, housed in a suitable housing attached to the side of the sweeper, and the principal object of my invention is to provide novel means for yieldingly mounting the brush on said shaft, whereby when the sweeper is steered too 20 close to the curb, in which the gutter broom is operating to clean out the said gutter, the brush when so striking the curb, will not be 25 injured, nor will the shaft be bent, or the shaft housing broken, nor will any injury to the brush or its parts be caused. In practice the operator watches the gutter brush 30 continuously as a guide in steering the sweeper close to the curb of the street in which the sweeper is operating.

A further object of the invention is to provide novel means for yieldingly mounting the brush on its shaft, whereby when 35 the brush holding disk comes in contact with the curb the brush will change its lateral position relative to the shaft, but will maintain its normal angularity with respect to the shaft, so as not to alter the angularity 40 of the brush with the pavement, the brush being moved laterally in a plane parallel with the normal plane of the brush. It has been found in actual practice that there is a 45 certain angularity between the brush and pavement wherein the brush will give most efficient results.

I will explain the invention with reference to the accompanying drawings which 50 illustrate one practical embodiment thereof to enable others to adopt and use the same, and will summarize in the claims the novel features of construction and novel combinations of parts, for which protection is desired.

In the drawings:

Fig. 1 is a side elevation of a conventional street sweeper showing my novel gutter brush mounted thereon.

Fig. 2 is an enlarged vertical section through the brush, and its novel attaching means to the adjacent end of its shaft showing the brush in its normal position.

Fig. 3 is an enlarged section through the brush and its novel attaching means to the brush shaft, showing same in position as assumed when jammed into a curb or other obstacle.

Fig. 4 is a top plan view of the brush and its novel attaching means.

Fig. 5 is an enlarged detail section on the 70 line 5—5, Fig. 2.

As shown in the drawings, my novel gutter brush 1 is adapted to be mounted at the side of a street sweeper S, said brush 1 being yieldingly mounted on a vertical shaft 75 2 rotatably housed in suitable housing 2^a attached to the side of the sweeper S in any desired manner, said shaft 2 and housing 2^a being preferably disposed at a slight angle to the vertical to cause the brush 1 to contact with the pavement with an angularity which will give most efficient sweeping results.

As shown, each brush 1, preferably comprises a plurality of replaceable wood segments 1^a having outwardly flaring bristles, which segments are preferably bolted into a pressed steel cup 1^c so as to be readily replaceable therein. Preferably, the top face of the cup 1^c is provided with an axial opening 1^d of relatively large diameter for the passage therethrough of the end of the shaft 2, as shown in Figs. 2 and 3 and exterior to the opening 1^d are a plurality of holes 1^e (four being shown) equally spaced on a 85 suitable pitch diameter.

On the lower end of shaft 2 is a spider 3, having a hub portion 3^a provided with an axial bore, which hub portion is preferably keyed to the shaft 2 so as to be rotated thereby, and is prevented from falling off the lower end of shaft 2 by means of a washer interposed between the end of the hub 3^a and a nut 2^c threaded onto a reduced extension on the end of shaft 2.

Integral with the hub portion 3^a is a rim portion 3^b which is preferably disposed in a plane above that of the transverse axis of

the hub portion 3^a, giving the spider 3 a substantially cup shaped form, and suitable openings 3^c may be provided in the spider intermediate the rim 3^b and the hub 3^a to give lightness to said spider 3.

In said rim 3^b, disposed on a pitch circle of same diameter as that of the holes 1^e in cup 1, are a like number of holes 3^d, and of same diameter as the holes 1^e.

10 Extending through each aligned pair of holes 1^e, 3^d, is a bolt 4 of suitable size and length (4 such bolts being shown in the drawings), each bolt 4 being retained in place by nuts 4^a which are prevented from working loose from said bolts by means of locking means 4^b, said bolts loosely securing the cup 1 to the spider 3. Around each of said bolts 4 is a spring 4^c interposed between the adjacent faces of cup 1 and spider 3 to normally press said spider and cup apart, and springs 4^c being preferably held concentric with said bolts 4 by means of spacing washers 4^d and 4^e, of suitable diameter around the bolts 4 at each end of said springs.

As shown in Fig. 5, the bolt heads and nuts are preferably formed parti-spherical, so that the bolt heads and nuts form substantially ball and socket connections between the bolt and the cup 1 or spider 3.

35 By using my novel means for yieldingly connecting the brush to its shaft, when the sweeper is run too close to the curb, the brush cup 1 will strike the curb C as shown in Fig. 3, and be shifted transversely or laterally of the shaft 2, without changing the angularity of the brush 1 with respect to the shaft 2 by reason of the arrangement of the bolts 4, and springs 4^c on said bolts between the cup 1, and the spider 3, which connection permits the bolts 4 to assume angular positions with respect to the shaft 2, and as the bolts 4 are all of the same length the brush 1 will be shifted laterally or transversely in a plane parallel with its normal working plane.

50 The springs 4^c tend to yieldingly press the brush 1 away from the spider 3, when under compression, and cause the brush 1 to be restored to its normal position coaxial with the shaft 2, when the obstacle is removed or when the brush is drawn out of contact with the curb C.

55 By adjusting the units 4^a the tension or compression in the springs 4^c may be increased or decreased to vary the resistance of the brush 1 against lateral displacement, and also, such adjusting will vary the effective length of the bolts 4 to true the brush 1 with the shaft 2.

60 Thus my yielding brush connection will prevent injury to the brush, shaft, or shaft housing when the brush is accidentally jammed into a curb or the like, and when so jammed thereagainst, the brush will con-

tinue to operate equally as efficiently as in normal operation, by maintaining the same angularity with respect to the pavement or shaft at all times. My yielding connection is efficient, cheap in construction, durable, and strong in operation, and gives a longer life to the brush, shaft and shaft housing.

I claim:

1. In combination a shaft; a brush; and means for yieldingly mounting the brush on said shaft, for movement axially, and transversely of said shaft and maintaining the axes of said shaft and brush parallel.

2. In combination a shaft; a brush; means for yieldingly mounting said brush on said shaft for movement axially, and transversely of said shaft and maintaining the axes of said shaft and brush parallel; and including means for adjusting the brush into normal coaxial relation with respect to said shaft.

3. The combination of a shaft; a member mounted on said shaft; a brush; means mounting said brush on said member for movement axially and transversely of said member, and maintaining the axes of the brush and shaft in parallel relation; and means yieldingly pressing said brush away from said member.

4. In combination a substantially vertical shaft; a member mounted transversely on the lower end of said shaft; a brush; means for mounting said brush on said member for movement axially and transversely of said member; and maintaining the axes of said shaft and brush in parallel relation; and including means for adjusting the brush into normal coaxial relation with respect to said member.

5. The combination of a shaft; a spider mounted transversely on said shaft; a brush; a plurality of parallel rods loosely connecting said brush and spider in normal parallel relation; springs around said rods interposed between the spider and brush, whereby when said brush is moved transversely of said shaft the rods will maintain the brush and spider in parallel relation.

6. The combination of a substantially vertical shaft; a spider mounted transversely on the lower end of said shaft; a brush; a plurality of bolts loosely connecting said brush and spider; nuts on said bolts for adjusting the spider and brush into normal parallel relation; springs around said bolts interposed between the spider and brush; the heads and nuts of said bolts being rounded; whereby when the brush is moved transversely of said shaft the bolts will maintain the brush and spider in parallel relation.

7. The combination of a substantially vertical shaft; a horizontal spider mounted on the lower end of said shaft; a circular brush; a plurality of bolts spaced evenly on a circle coaxial with said shaft and

loosely connecting the brush and spider; a spring around each said bolt interposed between the spider and brush; a head and a nut on each bolt for adjusting the effective length thereof, and for adjusting the brush into normal coaxial relation to said shaft; whereby the brush may be moved transversely of said shaft maintaining the axes of said brush and shaft in parallel relation.

10 8. The combination of a substantially vertically disposed shaft; a horizontal spider mounted on the lower end of said shaft; a circular brush; a plurality of bolts loosely connecting said brush and spider, said bolts

being spaced evenly on a circle concentric with said shaft; a spring around each said bolt interposed between the spider and brush; a head and a nut on each bolt for adjusting the tension of the spring, and for adjusting the brush into normal coaxial relation to said shaft; said bolt heads and nuts being rounded; thereby permitting lateral movement of said brush with respect to said shaft, and maintaining the axis of said brush parallel to said shaft.

In testimony that I claim the foregoing as my own, I affix my signature.

WILLIAM LIPP HARRIS.
